US00D970610S

(12) **United States Design Patent** (10) **Patent No.:** **US D970,610 S**
Kraft et al. (45) **Date of Patent:** **** Nov. 22, 2022**

(54) **BUSINESS FORM HAVING A WRISTBAND WITH SLOTS**

(71) Applicant: **Ward-Kraft, Inc.**, Fort Scott, KS (US)

(72) Inventors: **Roger Kraft**, Fort Scott, KS (US);
Gina Staudinger, Louisburg, KS (US);
Phil Quick, Fort Scott, KS (US)

(73) Assignee: **Ward-Kraft, Inc.**, Fort Scott, KS (US)

(**) Term: **15 Years**

(21) Appl. No.: **29/778,485**

(22) Filed: **Apr. 13, 2021**

(51) LOC (13) Cl. **19-01**

(52) U.S. Cl.

USPC **D19/1**

(58) **Field of Classification Search**

USPC D11/3-5; D19/1-8; D20/22, 27, 99;

D24/189

CPC A44C 5/00; A44C 5/0007; A44C 5/0053;

Primary Examiner — Abraham Bahta

(74) *Attorney, Agent, or Firm* — Avek IP, LLC

(57) **CLAIM**

The ornamental design for a business form having a wristband with slots, as shown and described.

DESCRIPTION

FIG. 1 is a front view of the business form having a wristband with slots; and,

FIG. 2 is a back view of the business form having a wristband with slots of FIG. 1.

The dash-dot-dot-dash lines in FIG. 2 illustrate die cuts that form part of the claimed design. The dashed lines shown in FIGS. 1 and 2 do not form a part of the claimed design.

1 Claim, 2 Drawing Sheets
